ROTARY MULTIPLE PUNCHING PRESS

Joseph Praturlon, Asnieres, France

Application December 5, 1949, Serial No. 131,153
In France December 24, 1948

2 Claims. (Cl. 164—99)

1

This invention relates to a novel press for performing any kind of punching, stamping and bending operations on a continuous band of sheet-metal and its main object is to provide a press which is capable of a considerably greater output than the heretofore known presses of the kind referred to.

The press according to the invention is mainly characterised in that it comprises a plurality of elementary presses mounted in star formation on a rotary support revolving about a horizontal axis, in such manner that they participate in its revolution and are capable of lateral displacements in a direction parallel to the axis of revolution, feeding means advancing the band of sheet-metal to be worked upon along a path comprising a curved portion concentric with said axis of revolution and imparting to said band in said curved portion an angular speed equal to that of the rotary support and the elementary presses mounted thereon, guiding means controlling the lateral displacements of said elementary presses so as to maintain permanently a determined number of them in a common vertical plane in which their working tables coincide with said curved portion of the sheet-metal band and to maintain the other elementary presses out of the path of said band, and actuating means actuating the working tools of each elementary press during its passage in said vertical plane.

Each elementary press may of course be of any type designed in view of the accomplishment of the desired work, such as punching, punching-stamping, punching-bending, etc.

In a preferred embodiment, to which the invention is however not limited, the rotary multiple press further presents one or more of the following features:

(a) The top of the working table of each elementary press has the shape of a portion of a cylindrical surface concentric with the axis of revolution and the sheet-metal band is applied by its tension on the tables of the elementary presses located in the above-mentioned vertical plane which constitutes the working zone, so that said band is frictionally advanced by said tables, as far as the point where it leaves them. In most cases, the band is at any time engaged by the tools of at least one of the elementary presses, the gripping action of which contributes in the correct advance of the band.

(b) The body of each elementary press is provided with a roller mounted on a vertical axis and engaging a fixed cam groove the shape of which

is determined in view of the control of the lateral displacements of each elementary press.

(c) One or more fixed cams are provided in the working zone and cooperate with corresponding rollers mounted on the tools of each elementary press, for controlling the movements of said tools, eventually in combination with return springs.

Other features and objects of the invention will appear from the following description, reference being made to the accompanying drawings, in which:

Figs. 1 and 2 show by way of example an embodiment of the press according to the invention, Fig. 1 being a front elevation and Fig. 2 a vertical section, at a larger scale, on line II—II of Fig. 1.

Figs. 3 and 4 show respectively in a side view and in a partially sectional front view an embodiment of an elementary press adapted to be mounted on the rotary multiple press according to the invention.

Figs. 5 is a front view of another embodiment of an elementary press which can be mounted on the rotary multiple press according to the invention.

Fig. 6 is a side view of a double-acting elementary press also adapted to be mounted on the rotary multiple press according to the invention.

Fig. 7 is an elevational view of twin presses according to the invention.

Figs. 8 and 9 are plan views showing two examples of cuttings that can be made by twin presses in a sheet-metal band.

In the embodiment shown in Figs. 1 and 2, the rotary multiple press comprises a frame 1, a removable bearing support 2, and a horizontal shaft 3 rotatably mounted in bearings provided in said frame and support and driven, for example, through gears 4, 5 and a pulley 6.

On a portion 3a of the shaft 3 is keyed a disk 7 formed on one of its sides with regularly spaced projections 8, between which are radially mounted the elementary presses, for example sixteen in number, as shown at P¹ to P¹⁶.

The body b of each elementary press is slidably keyed on a central hub 9 which is driven by the shaft 3 through keys 10. To this effect, each body b may have a foot portion 11 which is slidably engaged in a longitudinal groove 12 formed in the hub 9.

On the other hand, the body b of each elementary press has on each side a guide 13 which slides in a groove 14 formed in the corresponding projection 8 of the disk 7. The slides 13 are held in

the grooves 14 by the front edge 15a of a ring 15 secured to the circumference of the disk 7.

On each sliding carriage formed by two slides 13 is mounted a roller 16 rotatable about a vertical axis and engaged in the groove 17 of a cam 18 secured in any convenient manner to the machine frame 1. This groove 17 acts upon the rollers 16 to control the lateral movements of each press body b, in a direction parallel to the shaft 3, as it will be described hereinafter with more detail.

The working table t of each elementary press is shaped so that its top forms a portion of a cylindrical surface concentric with the shaft 3, and the groove 17 is shaped in such manner that at every moment a certain number of the elementary presses (in the shown example the seven presses P¹ to P⁷) are located in a common vertical plane (X—X in Fig. 2), so that the tops of their tables t compose a portion of a nearly continuous cylindrical surface on which the sheet-metal band F to be worked upon is pressed, so that this band is carried along by the rotation of the tables, as far as the point where it leaves them, which is the case at the press P⁷ in Fig. 1. The band F, which is supplied by a reel (not shown on Fig. 2 but indicated at Bd on Fig. 7), arrives for example between a pair of rollers 19 mounted on a support at the foot of the machine, passes over the tables t of the seven presses P¹ to P⁷ located in the above mentioned vertical plane X—X, then descends and passes between another pair of rollers 19' and finally leaves the machine, towards an upwinding device which may be, for example, of the known friction drive type which imparts to the band a constant linear speed. The natural resistance against rotation of the supply reel (Bd) is generally sufficient to ensure an adequate tension of the band F. If this is not the case, adjustable braking means may be applied to said reel or to the rollers 19. Such means are however generally not necessary, since in most cases the tools of at least one of the elementary presses are at any time in engagement with the band F, so that the latter is advanced not only by its frictional engagement with the tables t, but also by the gripping action of the working tools.

The groove 17 of the cam 18 is further shaped in such manner that every elementary press, after passing during its revolution in the above mentioned vertical plane X—X, which constitutes the working zone, is retracted with respect to said plane so as to clear the path of the sheet-metal band F. Thus, in the present example, all the elementary presses with the exception of the seven upper ones P¹ to P⁷, which are advanced in the above mentioned vertical working plane X—X, may be located in another common vertical plane Y—Y, to the rear of the working plane (more to the right on Fig. 2).

Apart from what has been said above relating to the working tables and the guiding means of the elementary presses, the latter may be of any type adapted to perform the desired operations, such as punching, punching-stamping, punching-bending, etc., and each of them may comprise one or more working tools.

Thus, the rotary multiple press according to the invention may be equipped with elementary punching and stamping presses of the type shown on Figs. 3 and 4, in which c is the punching tool, p the die, f the work-holder and e the stripper. In this embodiment of the press, the punching tool c is integral with a slide c¹ the head of which carries two rollers 20 and 21, mounted on hori-

zontal axes. Two fixed cams 22 and 23, mounted in the front part of the machine frame 1, are adapted to cause respectively the gradual lowering and subsequent lifting of the punching tool c, during that portion of the path followed by each elementary press which is located in the plane X—X (Fig. 2), by acting respectively upon the rollers 20 and 21. These parts are of course designed in such manner that the work of each elementary press is finished and the formed article is ejected when the considered elementary press reaches the end of the above mentioned portion of the path (position of press P⁷ in Fig. 2). At this point are provided adequate means, such as a receiving hopper, for the evacuation of the finished articles.

The rotary multiple press of the invention may also, for example, be provided with elementary punching and stamping presses of the kind shown on Fig. 5, in which the head of the punching tool slide c¹ is hingedly connected to a lever l which is pivotally mounted on the press body b and carries at its free end a roller 24 engaging a cam 25. In this case, the cam 25 may be double-sided, one side controlling the lowering of the tool and the other its subsequent lifting.

According to still another example, the machine according to the invention may be provided with double acting elementary presses of the type represented on Fig. 6. In this case, the slide c¹ carrying the punching tool is provided with two rollers 26 upon which act two identical cams 27, while another slide p¹, which carries the die, is provided with a roller 28 engaging a cam 29. The lifting of the slides c¹ and p¹ is effected by springs (not shown).

In addition to its great output, the multiple press according to the invention has the further advantage that it can be mounted in series with other presses of the same type, so that a plurality of multiple presses mounted one behind the other can work on the same continuously advancing sheet-metal band F, so as to use as much as possible of its surface.

As shown for example on Fig. 7, two multiple presses according to the invention can be combined to form a twin press through which is fed a sheet-metal band F unwound from the supply reel Bd and wound up on the receiving reel Be. The latter is advantageously rotated by means of a frictional drive, in such manner that the linear speed of the band F remains constant in spite of the variations of the diameter of this reel.

When each of the elementary presses mounted on these two multiple presses punches a single article out of the band F, the distance between the axes of the two machines can be determined in such manner that the holes d² punched out by the second machine are located between the holes d¹ punched out by the first machine (see Fig. 8).

When each of the used elementary presses comprises a plurality of tools, for example three, the twin formation of two multiple presses may be realized in such manner that the holes d¹ and d² punched out respectively by each of them are judiciously interpolated (as shown on Fig. 9).

It will be understood that the invention is not limited to the embodiments which have been described with reference to the drawings and that it extends equally to any other embodiment lying within the scope of the appended claims.

I claim:

1. A rotary multiple press for operating on a continuous band of sheet material moving in an

arcuate path which comprises: a frame; a rotary member rotatably supported on a horizontal axis by said frame and including a hub portion, a disc portion and a drum portion surrounding said hub portion; horizontal sets of guide elements on the outer surface of said hub portion and on the inner surface of said drum portion; a plurality of individual radial band-supporting and pressing devices slidably supported in both said sets of guide elements and disposed adjacent to each other; each of said devices including a table protruding therefrom and surrounding the end of said hub portion away from said disc portion and a cooperating pressing tool radially movable in each said device; said tables forming the sole supporting and rotating means for said band over a substantial arc of circle in said arcuate path; a first cam means on the frame for axially displacing said devices and constructed and arranged to bring said devices in supporting relation with said band as the latter enters said arc and to retract said devices away from the arcuate path of said band toward said drum portion and to remove said pressing tools from said path as said band

leaves said arc; and a second cam means on the frame for radially actuating said pressing tool alternatively in and out of contact with said band within said arc.

- 5 2. A press as claimed in claim 1, in which the radial axis of each said pressing tool intersects said arcuate path while said devices travel over said arc.

JOSEPH PRATURLON.
